UNITED STATES PATENT OFFICE.

JOHN WIERNICKI, OF GLASSPORT, PENNSYLVANIA.

WRENCH.

1,019,575.

Specification of Letters Patent.

Patented Mar. 5, 1912.

Application filed August 28, 1911. Serial No. 646,845.

To all whom it may concern:

Be it known that I, JOHN WIERNICKI, a subject of the Czar of Russia, residing at Glassport, in the county of Allegheny and

5 State of Pennsylvania, have invented certain new and useful Improvements in Wrenches, of which the following is a specification, reference being had therein to the accompanying drawing.

10 This invention relates to wrenches, and more particularly to that type commonly styled a pipe wrench, and employed for rotating pipes and objects having cylindrical or rounded surfaces.

15 The primary object of my invention is to provide a quick acting wrench of the above type that consists of comparatively few parts, inexpensive to manufacture, and easy to assemble.

20 Another object of this invention is to furnish a wrench of the above type with a normally open adjustable jaw that will co-operate with the fixed jaw of a wrench in positively gripping a surface.

25 A further object of this invention is to provide a wrench of the above type that can be easily manipulated and advantageously used by plumbers and other artisans.

These and such other objects as may hereinafter appear are attained by a mechanical construction that will be presently described and then claimed.

Reference will now be had to the drawing, wherein—

35 Figure 1 is a side elevation of a portion of a wrench partly broken away and partly in section; Fig. 2 is a front elevation of the same, and Fig. 3 is a horizontal sectional view taken on the line III—III of Fig. 1.

40 A wrench in accordance with this invention comprises a handle 1, having a longitudinal recess 2 formed therein extending from the outer end of the handle to a point in proximity to the inner end thereof. This

45 recess is rectangular in cross section, with one side thereof open and this side of the recess is adapted to be closed by a detachable face plate 3 that is secured to the handle 1 by screws 4 or other fastening means extending through the plate 3 into openings 5 provided therefor in the handle 1.

50 Formed integral with the outer end of the handle 1 is a fixed jaw 6, having a central opening 7 alining with the recess 2. The jaw 6 extends from the front and rear sides of the handle, and the rear end of the jaw

presents a flat gripping surface 8, while the forward end of the jaw has an offset 9 presenting a serrated or toothed gripping surface 10.

60 Slidably mounted in the opening 7 and recess 2 is a shank 11 that is rectangular in cross section, with the lower front edge thereof toothed or provided with transverse teeth 12. The outer end of the shank 11 has a jaw 13, with the rear end thereof presenting a gripping surface 14 adapted to co-operate with the surface 8 of the jaw 6 in gripping flat surfaces or the facets of a nut. The forward end of the jaw 13 is 70 curved, as at 15 and provided with a claw 16'. The curved forward ends of the jaw 13 co-operate with the forward end of the jaw 6 in gripping a pipe.

75 Interposed between the inner end of a shank 11 and the bottom of a recess 2 is a coil compression spring 16, adapted to normally maintain the shank 11 in an extended position with the jaw 13 open. To retain the jaw 13 in adjusted position, the handle 80 1 is provided with a slot 17, and extending into the slot is the toothed head 18 of a flat resilient locking member 19. The member 19 has the lower end thereof riveted or otherwise secured, as at 20, in the inner 85 end of the recess 2, and the outer end of the member is adapted to normally engage the shank 11. The outer side of the toothed head 18 has apertured lugs 21 pivotally connected to a link 22, and this link is pivotally connected, as at 23, to the outer end of a lever 24. The lever 24 is fulcrumed upon a pin 25 arranged transversely of the slot 17. The inner end of the lever is bent outwardly, as at 26, and interposed between 90 the inner end of said lever and the handle 1 is a coil compression spring 27. The handle 1 is cut away, as at 28, and provided with a guide pin 29 for the spring 27, whereby said spring cannot become accidentally displaced.

95 When the inner outwardly bent end of the lever 24 is pressed inwardly toward the handle 1, the head 18 of the member 19 is moved out of engagement with the shank 105 11, thereby allowing the spring 16 to move the shank and open the jaw 13. After the jaws 6 and 13 have been placed over the part to be gripped, the jaw 13 can be pushed toward the object whereby both of said jaws 110 will grip the object. The teeth of a shank 11 shift over the head 18, said head re-

ceding until the jaw 13 has been correctly positioned; then said jaw is locked by the member 19 and the wrench can be used for rotating the object.

5 The wrench in its entirety can be made of light and durable metal and of various sizes.

What I claim is:

10 A wrench comprising a handle having a centrally disposed longitudinal recess, a jaw integral with the outer end of the handle having a centrally disposed opening aligning the said recess, a face plate detachably mounted upon the handle for closing it, and having its outer end abutting against said jaw, a shank slidably mounted in said opening and recess having one edge toothed, a jaw integral with the shank opposing the jaw of the handle, said handle having its 15 front provided with a slot opening into said

recess, a locking member fixed at its inner end to one wall of said recess and having its outer end provided with a plurality of teeth normally engaging the toothed edge of the shank for maintaining the latter 25 from movement, a spring controlled lever pivotally mounted in said slot and normally engaging said locking member for maintaining it in engagement with the shank, and a coil spring interposed between the inner end 30 of the shank and the inner end of said recess for forcing the shank outwardly from the handle when the teeth of the lever are clear of the teeth of the shank.

In testimony whereof I affix my signature 35 in the presence of two witnesses.

JOHN WIERNICKI.
